UNITED STATES PATENT OFFICE

2,605,357

POWER DIVIDER CIRCUIT

Winfield W. Salisbury, Cedar Rapids, Iowa, assignor, by mesne assignments, to the United States of America as represented by the Secretary of the Navy

Application September 14, 1945, Serial No. 616,415

8 Claims. (Cl. 178—44)

1

This invention relates to a radio frequency power divider circuit, and particularly to one where the power may be divided in any suitable proportion between two outputs without materially changing the combined impedances of these outputs as seen from the input.

It is therefore an object of this invention to provide a means for dividing in any suitable proportion the radio frequency power output to a pair of transmission lines.

It is another object of this invention to provide a means for dividing in any suitable proportion the radio frequency power output to a pair of transmission lines and having incorporated therewith a means for regulating said proportion at will.

It is another object of this invention to provide a transmission line construction having an input line, and a pair of output lines joined thereto with a means for dividing in any suitable proportion the power output from each of said parallel output lines without materially disturbing the effective terminating impedance of said input lines.

Other objects and features of the present invention will become apparent upon a careful consideration of the following detailed description when taken together with the accompanying drawing, wherein:

Fig. 1 is a sectional elevational view of an embodiment of the invention.

Fig. 2 is a cross-sectional view taken along the line II—II of Fig. 1.

Fig. 3 is a generally sectional elevational view of a second embodiment of the invention.

Fig. 4 is a sectional view taken along the line IV—IV of Fig. 3.

An embodiment of the present invention is shown in Fig. 1, the input transmission line is at 100 and the output transmission lines are shown at 101 and 102. The outer conductors of the three transmission lines connect together at a common junction, the power dividing arrangement being provided in the circuits of the inner conductor.

The end portion 103 of the inner conductor of the transmission line 100 is mounted for axial rotation in the ball bearings 104 and is separated from the remainder of the inner conductor 100a of the transmission line 100 by a rotating joint of the contactless type formed by the hollowing out of the left-hand end of the conductor 103 and the projection of an extension 100b of the conductor 100a into the hollowed out portion of the conductor 103 for an electrical length of approxi-

mately a quarter-wave length, in accordance with the principles described in my patent application, Serial No. 478,793, filed March 11, 1943, now U. S. Patent Serial No. 2,541,836 of February 13, 1951.

5 The outer conductor of the transmission line 100 is enlarged slightly in the neighborhood of the junction. In the space thus provided are mounted two semi-cylindrical conducting segments 106 and 107 having axial lengths of approximately a quarter-wave length and oriented coaxially with the conductor 103. The segment 106 is electrically and mechanically connected to the inner conductor of line 101 and the segment 107 is electrically and mechanically connected to the inner conductor of line 102 and the respective connections are made at one end of the segments 106 and 107. Within the segments 106 and 107 are two more segments coaxial therewith and also of an axial length approximately a quarter-wave length, these segments begin to show at 108 and 109. The segment 108 is preferably approximately semi-cylindrical, although it may, if desired, be smaller in circumference, that is, it may be only a quarter cylinder or the like. The segment 108 is mounted on both ends, preferably by soldering, on suitable flanges of the conductor 103, such flanges being shown at 110 and 111. The segment 109 is mounted on the flange 111 but its left-hand axial extremity is free and makes no contact with either the flange 110 or with the neighboring portion of the conductor 103. The segment 109 has the function of a shield to reduce coupling between the left-hand portion of the conductor 103 and one of the outer segments when the segment 108 is located wholly opposite the other of the outer segments.

40 The right-hand portion of the conductor 103 carries a choke member 113 which is adapted to provide a radio-frequency short circuit between the conductor 103 and the immediately adjacent portion of the outer conducting structure of the junction, in accordance with the principles described in my above-mentioned patent application. The choke member 113 defines an annular cup having an electrical length of approximately a quarter-wave length, connecting at its right end with a narrow clearance space 114, having an electrical length also approximately equal to a quarter-wave length, so that a low radio-frequency impedance is presented at the left-hand end of the clearance 114 as desired. The distance between the left-hand end of the choke member 113 and the flange 111 is made to be approximately equal to a quarter-wave length, so that the portion of transmission line extend-

ing to the right of the flange 111 acts as a resonant stub, and therefore, has a minimum interference with transmission of energy around the junction. Rotation of the conductor 103 will cause the circumferential position of the segment 108 to be varied. In one position of the conductor 103 the segment 108 may be in close proximity to the segment 106. The segments 108 and 106 would then constitute a quarter-wave length transmission line open-circuited at the right-hand end, so that a relatively low radio-frequency impedance would appear across the left-hand end of such transmission line. Power may then be transmitted with relative ease from the transmission line 100 to the transmission line 101. As the segment 108 is moved from such position by rotation of the conductor 103, some coupling will take place with the transmission line 102 as well as with the transmission line 101 and the power transfer to the transmission line 101 will be reduced because the characteristic impedance of the transmission line constituted by the segments 106 and 108 will be increased. Thus an increasing proportion of the input power is diverted to the transmission line 102, until finally practically all of the input power is communicated to the transmission line 102 when the segment 108 is nearest to the segment 107 and is shielded from the segment 108 by the segment 109. A radio frequency power dividing circuit similar to the above-described embodiment is shown and claimed in U. S. Patent Serial No. 2,555,154, issued November 29, 1951, to R. C. Raymond and assigned to the same assignee as the present invention.

Another embodiment of the present invention is shown in Figs. 3 and 4. In Fig. 3 the input transmission line is shown at 117 and the output transmission lines are shown at 118 and 119. The transmission line 117 passes first through a rotating joint 120, which may be of a type described in my abovementioned patent application, to connect with a transmission line 121, which is adapted to be rotated bodily about its axis by means of the worm gear 122 and the worm 123. The worm 123 may be actuated by any suitable driving means.

Each of the transmission lines 121, 118, and 119 has its respective conductors connected to a pair of quadrantal cylindrical segments. The disposition of these segments is best seen from Fig. 4. The conductors of the transmission line 121 are connected respectively to the segments 125 and 126; the conductors of the transmission line 118 are connected respectively to the segments 127 and 128, and conductors of the transmission line 119 are connected respectively to the segments 129 and 130. The segments connected to the conductors of any one of these transmission lines form an opposed pair of segments. As shown on Fig. 4, the segments 127, 128, 129 and 130 fit together (without actual contact, a small gap being maintained) to form a single cylinder interrupted only by narrow gaps. The segments 125 and 126 form an opposed pair curved to a smaller radius and oriented coaxially with the aforesaid cylinder. The segments overlap axially for a distance approximately equal to an electrical quarter-wave length in order to provide effective transfer of radio-frequency energy without actual contact in accordance with principles previously referred to, and are equally spaced over the entire adjacent cylindrical surfaces. Rotation of the transmission line 121 is adapted to rotate the segments 125 and 126 relative to the dis-

position of the outer segments and thereby gradually to change the relative distribution of coupling to the two output transmission lines. When the transmission line 121 is adjusted for maximum coupling to one of the output transmission lines, there will generally be some small power transfer to the other transmission line, but this will be very small although not exactly zero, the difference in power level being about 40 db. This degree of effectiveness is quite sufficient for the purposes of this invention.

In order to avoid undesired coupling from stray fields that may arise in the neighborhood of the switching arrangement, quarter wave choke cups 131, 132 and 133 are mounted respectively on the outside of the transmission lines 121, 118, and 119. These prevent transmission of radio-frequency current along the outside of these transmission lines. It is further to be understood in connection with the power divider apparatus that wherever the electrical lengths of a quarter or half wave length are specified, an odd multiple or an even multiple, respectively, of a quarter-wave length may be used equally as well. Likewise, where the term electrical length, is used, it is to be understood as meaning a physical length of such value as to give the electrical effect of the corresponding electrical length in free space. Thus, the electrical lengths mentioned are to be taken as including the contribution of "end effects." All distances referred to in terms of wave lengths are intended to be electrical lengths as defined above.

Although I have shown and described only certain specific embodiments of the invention, I am fully aware of the many modifications possible thereof. Therefore, this invention is not to be limited except insofar as is necessitated by the prior art and the spirit of the appended claims.

I claim:

1. A radio frequency power divider, comprising a coaxial input transmission line having inner and outer conductors, a pair of coaxial output transmission lines, a cylindrical joint, said input and output lines secured to said joint, a pair of opposed curved surfaces of predetermined length used to terminate the respective conductors of said input line in said joint, two pairs of quadrantal segments, each of said quadrantal segments used to terminate the respective conductors of said output lines, said quadrantal segments so positioned as to form a four segment cylinder circumscribing said pair of opposed curved surfaces, and means for rotating said curved segments with respect to said quadrantal surfaces.

2. A radio frequency power divider, comprising a coaxial input transmission line having inner and outer conductors, a pair of coaxial output transmission lines, a cylindrical joint, said output lines joined to said joint, a portion of said input line rotatably joined to said joint in coaxial relation with one of said output lines, a pair of opposed curved surfaces of predetermined length used to terminate the respective conductors of said input line in said joint, said opposed surfaces being positioned to provide a pair of segments of a diameter less than the outer diameter of said input line, two pairs of quadrantal segments, each of said pair of segments used to terminate a respective conductor of said output lines in said joint, said quadrantal segments so positioned as to form a four segment cylinder circumscribing said pair of opposed curved surfaces, said quadrantal segments overlapping said curved surfaces by any odd multiple quarter wave length,

and a means for rotating at will said portion of said input line.

3. A radio frequency power divider, comprising a cylindrical joint, an input coaxial line, and a pair of output coaxial lines extending into said joint, a pair of spaced substantially semi-cylindrical segments connected respectively to the inner and outer conductors of a portion of said input line, and positioned concentrically with the axis of said joint, two pairs of spaced quadrantial cylindrical segments also arranged concentrically with the axis of said joint, each pair of quadrantial segments being oppositely disposed and connected respectively to an inner and outer conductor of each of the output lines, the semicylindrical and quadrantial segments being spaced axially coextensive for an odd integral number of quarter wave lengths, and means permitting rotation of said semi-cylindrical segments and associated portion of the input line, whereby the input power may be distributed between said output lines without materially disturbing the combined impedance of said output lines as seen from said input line.

4. A radio frequency power divider comprising an input coaxial line, first and second output coaxial lines, an end section of said input coaxial line being freely rotatable about its longitudinal axis, a first pair of diametrically opposed cylindrical segments connected respectively to the inner and outer conductors of said rotatable section of said input coaxial line, said first pair of cylindrical segments being positioned concentrically with the axis of said rotatable section, two pairs of spaced quadrantial cylindrical segments also arranged concentrically with the axis of said rotatable section, the segments within each pair of quadrantial segments being diametrically opposed and connected respectively to an inner and outer conductor of a respective output coaxial line, said first pair of cylindrical segments being radially spaced from said quadrantial segments and axially coextensive with said quadrantial segments for an odd integral number of quarter-wave lengths.

5. A radio frequency power divider comprising an input coaxial line formed with a fixed section and a rotatable section, a rotatable joint connecting said fixed section and said rotatable section, means for controllably rotating said rotatable section, a first pair of cylindrical segments disposed at diametrically opposed points on an imaginary cylinder that is concentric with the axis of said rotatable section, said cylindrical segments being connected respectively to the inner and outer conductors of said rotatable section, two pairs of spaced quadrantial cylindrical segments arranged around a second imaginary cylinder concentric with the axis of said rotatable section, the segments constituting each pair of quadrantial segments being diametrically opposed and connected respectively to the inner and outer conductor of a respective output coaxial line, said first pair of cylindrical segments being radially spaced from said quadrantial segments and axially coextensive with said quadrantial segments for an odd integral number of quarter-wave lengths.

6. A radio frequency power divider comprising first and second output coaxial lines, an input coaxial line formed with a fixed section and a rotatable section, a rotatable joint connecting said fixed section and said rotatable section, means for controllably rotating said rotatable section, a first pair of cylindrical segments disposed at diametrically opposed positions about the axis of said rotatable section, said cylindrical segments being electrically connected to the inner and outer conductors, respectively, of said rotatable section and mounted so as to rotate therewith, two pairs of spaced quadrantial cylindrical segments also arranged about the axis of said rotatable section, the segments constituting each pair of quadrantial segments being disposed at diametrically opposed positions and connected respectively to the inner and the outer conductor of a corresponding output coaxial line, said first pair of cylindrical segments being radially spaced from said quadrantial segments and axially coextensive with said quadrantial segments for an odd integral number of quarter-wave lengths, and a conductive shield completely surrounding said rotatable section, said cylindrical segments, said quadrantial segments and the ends of said output lines to which said quadrantial segments are connected.

7. A radio frequency power divider as in claim 6 wherein said conductive shield includes first, second and third quarter-wave length chokes disposed on the outer conductors of said rotatable section and said two output lines respectively, said quarter-wave length chokes preventing transmission of radio-frequency current along the outside of the outer conductor.

8. A radio frequency power divider comprising a two-conductor input transmission line, first and second two-conductor output transmission lines, first and second pairs of spaced quadrantial cylindrical segments arranged about a common axis so as to form a substantially cylindrical surface, the segments constituting each pair being disposed at diametrically opposed positions and connected respectively to first and second conductors of a corresponding output transmission line, a third pair of quadrantial cylindrical segments disposed at diametrically opposed positions about said axis and connected, respectively, to a first and a second conductor of said input transmission line, said third pair of segments being radially spaced from said first and second pairs of segments and axially coextensive with said first and second pairs of segments for at least an electrical quarter-wave length, said third pair of segments being rotatable relative to said first and second pairs of segments to vary the division of power between said first and second output transmission lines.
